[57] CLAIM

The ornamental design for a film laminator for printed circuit boards, as shown.

DESCRIPTION

FIG. 1 is a front elevational view of a film laminator for printed circuit boards showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front, top and right side perspective view thereof.
